UNITED STATES PATENT OFFICE

GEORGE GLENN MOTT, OF PASADENA, CALIFORNIA

WINDOW SHADE

Application filed November 7, 1928. Serial No. 317,831.

This invention relates to improvements in window shades and the like and specifically may be considered as being an improvement over the construction disclosed in U. S. Letters Patent No. 549,769, issued November 12, 1895, to Joseph O. Dobson.

Briefly the construction disclosed in the above mentioned patent has a pair of slats between which the fabric forming the window shade extends which fabric is reversely bent upon itself between the slats and has its end encircling and enclosing the slats. Nails or equivalent fasteners are driven through the fabric and slats from the outside surface thereof to fasten the slats and fabric together. These nails or equivalent fasteners when so employed are disadvantageous in that they mar at least one side of the finished surface at the bottom of the window shade.

It is an object of this invention to provide an improved window shade having a pair of slats between which the fabric forming the window shade extends and which has its end encircling and enclosing the slats and to provide a construction for fastening the slats and fabric together which is so constructed that the exterior surface is not marred by the appearance of the heads or ends of such fastening means.

Another object of the invention is to provide a window shade construction having a pair of slats forming the shade stick between which the fabric forming the window shade extends which employs end staples which are driven into the ends of the slats for fastening the slats and fabric together and which employs a hollow rivet passing through the slats at the center thereof which hollow rivet not only fastens the slats and fabric together but also provides for the reception of the shade cord.

Another object of the invention is to provide a novel folding of the fabric so as to enclose the slats and present a finished surface thereon.

With the foregoing and other objects in view which will be made manifest in the following detailed description and specifically pointed out in the appended claims, reference

is had to the accompanying drawing wherein:

Fig. 1 is a partial view in perspective illustrating the window shade embodying the invention.

Fig. 2 is a view in end elevation of the shade.

Fig. 3 is a vertical section taken upon the line 3—3 upon Fig. 1.

Fig. 4 is a vertical section taken substantially upon the line 4—4 upon Fig. 1.

Fig. 5 is a partial view in perspective illustrating the manner in which the slats and fabric are assembled in forming one form of the improved window shade.

Fig. 6 is a perspective view of one of the end fasteners or staples used for connecting the slats together across their ends.

Fig. 7 is a vertical section through the lower portion of the window shade illustrating a modified form of construction embodying the invention.

Fig. 8 is a partial view in perspective illustrating a manner in which the slats and fabric may be assembled in forming the modification shown in Fig. 7.

Referring to the accompanying drawings wherein similar reference characters designate similar parts throughout the improved window shade consists of the fabric 10, forming the body or major portion of the shade and adapted to be rolled up on a roller or similar construction designated at 11. The shade stick at the bottom of the shade is formed of two slats 12 and 13 having horizontal bottom surfaces and vertical inner surfaces. The outer sides of the slats converge upwardly toward each other, both with respect to each other and with respect to the inner surfaces on their respective slats. The fabric 10 extends downwardly between the slats 12 and 13 and is reversely bent upon itself as indicated at 14 between the slats with the end of the fabric extending upwardly between the slats bent around the top of slat 12 as indicated at 15, downwardly over its outer side as indicated at 16 beneath the bottoms of the two slats as indicated at 17 then upwardly over the outer side of slat 13 as indicated at 18 and finally downwardly between the slats terminating as indicated at 19 near

the reverse bend 14. In this manner the fabric 10 suspends the curtain stick formed by the two slats from its center and also forms a finished surface over the outside of the two slats. A method of assembling the fabric 5 and slats is represented by Fig. 5 wherein the two slats 12 and 13 are laid on the fabric 10 near its bottom edge with the lower end of the fabric bent over against the interior 10 surface of slat 13. A tuck or pleat is taken in the fabric 10 forming the reverse bend 14 and this tuck or pleat is laid against the interior surface of slat 12. Suitable means for fastening the fabric to the slats may be 15 employed, such as metallic staples 20 driven through the fabric into the interior surface of slat 13 and through the reversely bent portions of the fabric into the interior surface of slat 12. It will be noted that the staples 20 or equivalent fasteners 20 are not long enough 20 to project through the slats. After the fabric is thus fastened to the slats the slats are folded upwardly against each other from the position shown in Fig. 5 to the position shown 25 in Figs. 2 to 4 inclusive.

A feature of the invention resides in then fastening the slats together so that they will clampingly engage upon the fabric and so that the finished surface provided by the 30 fabric 10 on the outside of the slats will not be marred. This is accomplished by forming a hole 21 through the slats and fabric at the center of the slats and fastening therein a hollow rivet 22. The hollow rivet thus 35 fastens the slats and fabric together and provides for the reception of the shade cord 23. As it is conventional to use some form of hollow rivet or grommet to receive the shade cord the use of the hollow rivet for this 40 purpose does not mar to an undue extent the finished surface on the outside of the slats. The hollow rivet 22 thus fastens the slats together at their centers and the slats are also fastened together at their ends. This is 45 accomplished by means of sheet metal staples 24 which have their sides converging upwardly and inwardly bent prongs 25 which are driven into the slats 12 and 13. These 50 staples connect the slats together at their ends and maintain them in clamping engagement upon the fabric 10. By virtue of the 55 fact that they are driven into the ends of the slats they do not mar or detract from the finished surface provided by the fabric 10 over the outside of the slats.

In Figs. 7 and 8 there is disclosed a novel manner for enclosing the slats 12^a and 13^a by the fabric 10^a. The slats 12^a and 13^a are laid in parallel relation near each other 60 and near the end of the fabric 10^a. The end of the fabric is then bent over against the interior surface of the slat 13^a and then is extended beneath the outer surface of slat 12^a, finally terminating at 65 about half way down from the top of the in-

terior surface of slat 12^a. The fabric 10^a is then given the pleat or tuck to provide the reverse bend 14^a and this pleat or tuck is positioned over the end 26 against the interior surface of the slat 12^a. Staples or 70 equivalent fasteners 20^a are then driven through the fabric into the interior surface of the slat 12^a. No fasteners, however, are driven through the fabric into the slat 13^a. After the staples 20^a have been driven the slats are folded upright with the slat 13^a shifting the required amount or partially 75 turning within the loop formed by the fabric 10^a enclosing it. When the two slats assume the upright position side by side as shown in Fig. 7 the hollow rivet 22 and the staples 24 may then be driven into the slats fastening 80 them and the fabric together.

From the above described construction it will be appreciated that a novel and advantageous window shade construction is provided wherein the stick of the shade presents a uniform, neat and attractive finished surface which is not marred nor detracted from by nails or equivalent fasteners which have 85 their heads exposed on one side or both sides of the stick. The only exposed fasteners are the ends of the hollow rivet 22 and the staples 24 and these are so arranged as not to be readily noticed nor to materially detract from the appearance of the shade.

Various changes may be made in the details of construction without departing from the spirit or scope of the invention as defined by the appended claims.

I claim:

1. A window shade having a pair of slats between which the fabric forming the shade extends, and a hollow rivet extending through the slats and fabric fastening the slats together and to the fabric, said hollow rivet being adapted to receive the shade cord and being the sole means securing the slats together intermediate the ends thereof.

2. A window shade having a pair of slats between which the fabric forming the shade extends, and a hollow rivet extending through the slats and fabric fastening the slats together and to the fabric, said hollow rivet being adapted to receive the shade cord, and means connecting the slats together across their ends.

3. A window shade having a pair of slats between which the fabric forming the shade extends, and means fastened to the ends of the slats serving to connect the slats to each other across their ends.

4. A window shade having a pair of slats between which the fabric forming the shade extends, and means fastened to the ends of the slats serving to connect the slats to each other across their ends and causing them to maintain clamping engagement upon the fabric.

5. A window shade having a pair of up- 130

- wardly tapering horizontal slats between which the fabric forming the window shade extends, and sheet metal staples having upwardly converging side edges driven into the ends of said slats serving to connect the slats to each other and to cause them to maintain 5 clamping engagement upon the fabric.
6. A window shade having a pair of upwardly tapering horizontal slats between 10 which the fabric forming the window shade extends, and sheet metal staples having upwardly converging side edges driven into the ends of said slats serving to connect the slats to each other and to cause them to maintain 15 clamping engagement upon the fabric, and a hollow rivet extending through the slats at the center thereof serving to fasten the slats and fabric to each other and providing for the reception of the shade cord.
- 20 7. A window shade having a pair of slats between which a fabric forming the shade extends, the fabric being reversely bent upon itself between the slats and having its end extending upwardly between the slats and then 25 extending around the slats on the exterior surfaces thereof to provide finished exterior surface thereon, and a hollow rivet extending through the slats and fabric fastening the slats and fabric together and providing for 30 the reception of the shade cord, said hollow rivet being the sole means securing the slats together intermediate the ends thereof.
8. A window shade having a pair of slats between which a fabric forming the shade extends, the fabric being reversely bent upon 35 itself between the slats and having its end extending upwardly between the slats and then extending around the slats on the exterior surfaces thereof to provide a finished exterior 40 surface thereon, and means for connecting the slats across their ends to each other.
9. A window shade having a pair of slats between which a fabric forming the shade extends, the fabric being reversely bent upon 45 itself between the slats and having its end extending upwardly between the slats and then extending around the slats on the exterior surfaces thereof to provide a finished exterior 50 surface thereon, a hollow rivet extending through the slats and fabric fastening the slats and fabric together and providing for the reception of the shade cords, and means connecting the slats across their ends to each other.
- 55 10. A window shade having a pair of slats between which a fabric forming the shade extends, the fabric being reversely bent upon itself between the slats and having its end extending upwardly between the slats and then 60 around the slats on the exterior surfaces thereof to provide a finished exterior surface thereon, fastening means driven through the fabric into the inner surface of one of the slats to fasten the fabric thereto, said fastening means having its head portions dis-
- posed between the slats, and means fastening the slats to each other.
11. A window shade having a pair of slats between which a fabric forming the shade extends, the fabric being reversely bent upon itself between the slats, and having its end extending upwardly between the slats and then 70 extending around the slats on the exterior surfaces thereof to provide a finished exterior surface thereon, fastening means driven through the fabric into the slats through the inner opposed faces, said fastening means having their heads disposed between the slats, and means fastening the slats together.
- In testimony whereof I have signed my 75 name to this specification.
- GEORGE GLENN MOTT.
